UNITED STATES PATENT OFFICE

PAUL R. HEYGEL, OF RIDGEFIELD, NEW JERSEY

REFRIGERATOR CONSTRUCTION

Application filed May 22, 1930. Serial No. 454,560.

This invention relates to a refrigerator construction and especially to the construction of the ice compartment.

In the class of refrigerators which is constructed to contain and hold an ordinary piece of ice, it is found that the ice chamber or compartment is subject to a great amount of wear and tear and is also subject to corrosion. It is common practice to use forty to sixty pounds of ice in the ordinary domestic refrigerator. The ice usually comes in one piece and is often thrown into the ice compartment in a careless manner so that the lining of the compartment is bent or broken.

It is a principal object of this invention to produce an ice chamber which is readily removable through the ordinary doors with which the conventional refrigerator is equipped so that the walls and lining which make up the ice compartment may be readily replaced at a small cost, if they become damaged in use.

It is another object to enable the manufacturer of the refrigerator to utilize a comparatively cheap material in the production of the walls and lining of the ice compartment. For instance, it may be and is desirable to line the main portion of the refrigerator with enamel or porcelain, but it may not be desirable to construct the lining of the ice compartment with such material. With my invention, it is possible to make this lining of comparatively inexpensive material, such as galvanized iron, which can be cheaply replaced without in any way disturbing the porcelain and enamel lining of the main body of the box.

Further features and objects of the invention will be more fully understood from the following detail description and the accompanying drawings, in which—

Fig. 1 is a front elevation of the right section taken through the interior of the refrigerator.

Fig. 2 is a perspective view of the removable lining of the ice chamber.

Fig. 3 is a section taken through 3—3 of Fig. 1.

Inasmuch as the construction of the outer portion of the refrigerator forms no part of

the present invention, it is believed that it is unnecessary to illustrate any more than the lining of the refrigerator and the furnishings thereof which pertain to and co-operate with the applicant's structure.

In Fig. 1, the lining of the refrigerator is illustrated at 1, and may be galvanized iron, porcelain, enameled sheet metal or other suitable material. The lining of the ice compartment is constructed in two parts 2 and 3. Part 2 is illustrated on the left side of the compartment, as viewed through the open door furnished for communication with this compartment, and part 3 is shown on the right side thereof.

Each comprises a back portion numbered 5 and 6 respectively, a side wall shown at 8 and 9, and a bottom portion 11 and 12. Each pair is equipped with engaging edges adapted to co-operate with the corresponding engaging edge of the other part.

In part 2, the vertical rear engaging edge is illustrated at 13, and the bottom engaging edge at 14. The co-operating corresponding engaging edge for the rear wall of part 3 is illustrated at 17.

The engaging edge of part 3 is equipped with a turn-over lip, along the entire edge thereof from one end to the other. This lip is turned over as illustrated at 19 and 19a, for instance, to form a U-shaped groove in which the edge portions of 13 and 14 are adapted to fit when the two halves of the ice compartment are installed within the refrigerator.

The bottom of the ice compartment is equipped with the usual air-circulating aperture in the center thereof, illustrated at 20, and the margin of which is raised to form a lip, shown at 21, so that water produced by the melting of the ice will be confined within the marginal portions of the bottom of the ice compartment and may be drained off therefrom through drain pipes 23 and 24 which connect with the drain openings 26 and 27 respectively. These drain pipes 23 and 24 are adapted to discharge into the funnel-shaped end 29 of drain pipe 30 which is equipped with the usual water seal 31 and discharge nozzle opening 32.

The interior of the refrigerator is equipped with suitable hooks 35, 36, 37, and 38, on the rear wall thereof, adapted to engage co-operating apertures 39, 40, 41 and 42 in the rear walls of the ice compartment lining.

- 5 The side of the refrigerator is equipped with a pair of hooks, one of which is shown at 45; these supporting hooks are adapted to engage in apertures 47 and 48 respectively, illustrated in Fig. 2. Each of the supporting 10 hooks is furnished with an indentation spaced from the lining of the refrigerator and adapted to receive the edge of the portions of the ice compartment so as to space the side and rear walls of the compartment away from the lining of the box, so that an 15 air space will exist to allow circulation of air therebetween, and thus obviate the collection of moisture which would eventually stain and corrode the lining of the refrigerator and the ice compartment. Suitable 20 spacing pads are positioned on the rear and side walls of the ice compartment, as illustrated at 46. We have seen fit to illustrate 25 four of these pads for the rear wall of the ice compartment, but wish it to be understood that a fewer or greater number may be used, if so desired. These pads may be made of 30 cork or rubber, and when made of these materials, it will be found that they possess a long life and will not stain or mark the 35 porcelain or enamel surface of the refrigerator lining. The front of the lower portion of the ice compartment is equipped with flanges 50 and 51, illustrated in Figs. 2 and 3, which are adapted to rest upon the sill 40 of the ice door compartment opening which is shown at 53 in Fig. 3. These flanges 50, 51, furnish a support for the front of the ice 45 compartment linings.

The outer wall construction of the refrigerator is indicated at B in Fig. 3. An ice pan 56 is adapted to be supported upon suitable legs 57 and 58, in a slightly raised 50 position over aperture 20 and substantially centrally disposed in regard to the ice compartment, and is illustrated as supporting a piece of ice I, as will be observed upon looking at Fig. 1. The outer edges of ice pan 55 55 extend beyond the marginal portions of opening 20 so that the water from the melted ice will not drain through the opening 20 into the interior of the ice box, but instead will be collected by the portions 11, 12, and 55 flow through apertures 26 and 27 to drain through the drain pipe 30 and be carried away.

The outside of the portion 3 may be 60 equipped with shelf-supporting brackets, as shown at 60 and 61. Corresponding brackets 62 and 63 are oppositely disposed therefrom and secured to the inner wall of the refrigerator. Shelves 65 and 66 may be placed upon these brackets so that they can be readily 65 removed therefrom, as so desired.

The removable ice compartment lining may be removed or installed through the ordinary ice compartment door. To install it, part 2 is first positioned and hung upon the hooks 36, 39, and 45, and then part 3 is hung upon corresponding hooks 37 and 38, so that the engaging edges thereof co-operate with the engaging edges of part 2 and the drain pipe, ice pan and shelves may be readily installed.

Desirably, as is illustrated in the drawings, and referred to hereinabove, my invention is effected by forming the ice compartment of a plurality of coacting parts, usually two and of substantially equal general dimensions, the component parts being arranged side-by-side to afford a substantially horizontal relationship at their bottom faces for the support of a common ice pan, or equivalent, the component parts being interfitted relative to one another and also individually supported, whereby one component part may be removed from its supporting position and through the ice charging door of the refrigerator, the remaining one or more component parts being subsequently removed.

Whereas I have described my invention by references to specific forms thereof, it will be understood that many changes may be made without departing from the spirit of the invention.

I claim:

1. In a refrigerator, an ice compartment separate from the remainder of the refrigerator, said ice compartment comprising a plurality of side-by-side aligned component parts, and means for removably positioning said parts in the refrigerator, whereby said parts may be readily replaced without disturbing other structural parts of the box.

2. In a refrigerator, an ice compartment separate from the remainder of the refrigerator, said compartment being formed of a plurality of interfitting side-by-side component parts, each component part having a dimension enabling it to be passed through the doors of the refrigerator, and means for detachably connecting said component parts in place within the refrigerator.

3. In a refrigerator, an ice compartment, separate from the remainder of the refrigerator and comprising a plurality of interfitting side-by-side aligned parts, said parts having their bottom faces substantially horizontally aligned, the dimensions of said parts individually affording the same to be readily passed through the doors of the refrigerator and assembled therein to form a complete ice compartment.

4. In a refrigerator, an ice compartment, comprising a plurality of parts arranged to be positioned in substantially horizontal alignment, the dimensions of said parts individually enabling the same to be passed through the ordinary doors of a refrigerator.

ator, and means for supporting said parts individually and jointly in said refrigerator so that the parts may be readily installed and removed without disturbing the construction of the remainder of the refrigerator.

5. In a refrigerator, an ice compartment, comprising two parts, each small enough to pass through the ordinary doors of the refrigerator, co-operating means on each part adapted to enable said parts to be assembled within the refrigerator in side-by-side alignment to form a complete ice compartment, and means for supporting said parts individually and jointly within the refrigerator in proper relationship to the remainder of the refrigerator.

10. 6. In a refrigerator, an ice compartment, comprising a plurality of parts arranged in side-by-side, substantially horizontal alignment, means for supporting said parts individually and jointly to form a complete unitary structure within the refrigerator, a single drain pipe and communicating drain gutter for each part adapted to co-operate with an ice support to collect and drain off the water produced by the melting of the ice within the compartment.

15. 7. In a refrigerator, an ice compartment, comprising a plurality of parts separate and distinct from the remainder of the refrigerator and adapted to be passed through the ordinary door of the refrigerator and readily assembled therein to form a complete compartment, and means for separately supporting said parts within the refrigerator.

20. In testimony whereof I have signed this specification this 12th day of May, 1930.
